SNUBBED TRUCK

Robert B. Cottrell, Chicago, Ill., assignor to American Steel Foundries, Chicago, Ill., a corporation of New Jersey

Application December 2, 1948, Serial No. 63,139

8 Claims. (Cl. 105—197)

This invention relates to railway car trucks of the stabilized type.

A general object of the invention is to design a truck incorporating novel stabilizing or friction means arranged to effectively damp various movements between the bolster and the side frame.

A more specific object of the invention is to provide a truck suitable for high speed service wherein angling and longitudinal movements of the bolster are yieldingly restrained and wherein the means employed to restrain such movements also frictionally snub lateral and vertical movements of the bolster.

The invention comprehends a novel truck including bolster and side frame members, the bolster member having lateral extensions associated with friction means and received therewith between spaced inboard and outboard friction surfaces on the frame member, the extensions tying the members together and being urged against the inboard surfaces by the friction means which engage the outboard surfaces.

The invention contemplates an arrangement wherein the extensions and the friction means engage each other in a manner accommodating angling movements of the bolster without disengaging the friction means from the related side frame surfaces.

A further object of the invention is to provide friction means of simple, rugged form and actuating means therefor reacting directly thereagainst and against a truck member, thereby providing a compact arrangement.

The preferred embodiment of the invention contemplates an arrangement wherein the bolster is partially carried by friction shoes wedged between the outboard friction surfaces of the frame and the bolster extensions, the shoes being supported on springs seated on novel spring support members mounted on the frame and removably interlocked therewith.

In the preferred embodiment of the invention the side frame is provided with spaced inboard and outboard friction surfaces which are of substantially equal vertical length and which are designed to afford substantially full face engagement for the respective bolster extensions and friction means during normal vertical oscillations of the bolster. The spring seat members are removable to accommodate assembly and disassembly of the bolster from below the side frame surfaces through the lower end of the bolster opening.

Another object of the invention is to design a bolster with novel laterally extending wing portions, each of the wing portions being of light weight skeletal construction and having pockets in the top sides thereof adapted to collect dirt to prevent the dirt from sifting between the parts of the associated friction assembly and thus accelerating wear between the parts or causing malfunctioning of the assembly.

These and other objects of the invention will be apparent from the specification and drawings, wherein:

Figure 1 is a fragmentary side elevational view of a car truck incorporating a preferred embodiment of the invention, only one end of the truck structure being shown as the arrangement is identical at opposite ends thereof;

Figure 2 is a view partly in section on line 2—2 of Figure 1, the bolster being shown in side elevation;

Figure 3 is a sectional view taken on line 3—3 of Figure 1; and

Figure 4 is a sectional view taken on line 4—4 of Figure 1.

2

Figures 5 and 6 illustrate a modification of the invention and are views comparable to Figures 1 and 2, respectively;

Figures 7 to 9 illustrate another modification of the invention, Figure 7 being a fragmentary side elevational view of a truck, with the outboard wall of the column broken away, and the shoe and associated bolster wing portion shown partly in vertical section on line 7—7 of Figure 9; Figure 8 being a view partly in section on line 8—8 of Figure 7, the bolster being shown in side elevation; and Figure 9 being a sectional view taken substantially on the line 9—9 of Figure 7.

Describing the invention in detail and referring first to the preferred embodiment illustrated in Figures 1 to 4, the truck comprises a side frame including tension and compression members 2 and 4, and a column 6 adjacent each end of the frame merging with said tension and compression members and defining a bolster opening 8 therewith.

20 The tension member beneath the bolster opening is of box-section and comprises spaced inboard and outboard webs 10 and 12 and spaced bottom and top chords 14 and 16, the top chord being widened beyond the normal lateral dimensions of the tension member and supporting 25 a spring plate 18 which is interlocked with the tension member by upstanding bosses 19, 19 on the top chord extending through complementary openings in the spring plate. The spring plate is contoured to position a group of bolster-supporting springs 20 seated thereon. The upper ends of the springs 20 seat against the bottom wall 22 of a box-section bolster, generally indicated 24, and are confined by spaced lugs 26, 26 on the bottom wall.

In addition to the bottom wall 22, the bolster 24 comprises a top wall 28, a side wall 30 at each side thereof, 35 and a longitudinally extending substantially vertical center rib 32 which with the side walls 30 interconnects the top and bottom walls of the bolster.

The bolster is provided at each side thereof with an integral lateral extension or wing portion generally designated 34 which is of skeletal construction, as may readily be seen in Figures 2 and 3. The extension comprises on its inboard side a substantially vertical wall 36 extending transversely of the bolster outwardly from the adjacent side wall of the bolster and is of a height substantially 45 equal to the depth of the bolster end. The extension also comprises a diagonal ledge or web 38 sloping upwardly toward the adjacent end of the bolster. The web 38 is integral with the adjacent side wall of the bolster and extends transversely of the bolster and at its lower 50 end merges with the inner side of wall 36 of the extension in an area intermediate the top and bottom thereof. The ends of webs 36 and 38 which are remote from the bolster are interconnected by a substantially vertical end wall 40. The form of the extension combines light 55 weight with strength and lends itself to good foundry practice.

A pocket 41 is formed in the extension by the webs thereof and wall 40 and the adjacent side wall 30 of the bolster, said pocket being open at the top of the extension and being adapted to collect dirt such as coal dust or cinders for a purpose hereinafter stated.

The extension is received within a U-shaped channel 42 in the adjacent column 6, the channel being defined by spaced inboard and outboard walls 44 and 46 and an 65 intermediate wall 48. The wall 44 is provided on its inner side with a friction plate presenting a flat substantially vertical friction surface 50 extending longitudinally of the frame and having complementary engagement with a wear plate 52 mounted on the inboard or external side 70 of web 36 of the wing portion 34. The wear plate 52 is preferably welded as at 54 to wall 36 of the wing portion 34.

The diagonal wall 38 of the extension 34 presents an external convex wedge surface 56 facing toward the adjacent end of the bolster and sloping diagonally upwardly. The surface 56 engages as at 58 a similarly sloping convex surface 60 on a friction shoe 62.

The shoe 62 is of skeletal construction and substantially triangular in side elevation, as best seen in Figure 2. The shoe 62 presents a substantially vertical surface 64 frictionally engaging a surface 66 extending longitudi-

3

nally of the frame approximately parallel to surface 50 on the friction panel on the inboard wall 44 of the associated column, said surface 66 being provided on a wear plate mounted on the inner side of the outboard wall 46 of the associated column. It will be noted that surfaces 50 and 66 may be formed integral with the respective column walls. The shoe 62 presents a spring seat 70

The bottom of the shoe 62 presents a spring seat 70 affording a seat for the upper end of an auxiliary, generally vertical, shoe-actuating spring 72. The upper end of 10 the auxiliary spring 72 is positioned on the seat 70 by means of a boss 74 formed on the bottom of the shoe. The lower end of the spring 72 seats as at 76 (Figure 1) on a spring seat member or casting 78, said casting comprising a top wall 80 with a boss 82 thereon affording 15 positioning means for the lower end of spring 72. The web 80 of the casting 78 straddles an auxiliary or secondary truss web 84, said truss web 84 merging at its inner extremities with the top surface of web 16 of the tension member at the lower end of the bolster opening 8 and intermediate its ends merging with the walls of the adjacent column and at its other end with a diagonal portion of the tension member in an area beyond the associated column 6, as will be readily understood by those skilled 20 in the art.

The casting 78 comprises inboard and outboard walls 90 and 92 which are disposed inboardly and outboardly of the secondary truss web, thus interlocking the casting with the frame against movement transversely of the frame. The lower ends of the webs 90 and 92 are provided with outturned flanges which afford seats for the casting against the top surface of the top chord 16 of the tension member. The casting 78 also comprises an end wall 94 interconnecting the adjacent extremities of the webs 80, 90 and 92. A lug 96 is formed on the lower end of wall 94 and extends into the bolster opening along the top surface of chord 16 of the tension member within the bifurcation 98 in the adjacent side of the spring plate 18. The securing lug 96 is provided with an opening 100 to receive a lug 102 on chord 16 to fasten the casting 78 against movement longitudinally of the frame. The lateral edges of the lug 96 adjacent the end wall 94 are connected by spaced gussets 104, 104 merging with the top surface of lug 96 and the external side of the end wall 94 of the casting to strengthen the connection between the lug and the casting.

It will be observed that the inboard and outboard webs 44 and 46 of the column merge at their upper ends with the compression member. The lower ends of the portions of the inboard and outboard webs 44 and 46 at the side of wall 48 of the column adjacent the bolster opening terminate at their lower ends approximately midway between the top and the bottom of the bolster opening and it will be observed from a consideration of Figure 2 that they are of substantially equal vertical length and are dimensioned to afford fullface bearing for the associated wing portion and shoe thereagainst during normal vertical movements of the bolster on the truck springs 20. The lower ends of walls 44 and 46 merge with the adjacent diagonal portion of the tension member outside the bolster opening. ¹ ₁ ² ₂ ³ ₃ ⁴ ₄ ⁵ ₅ ⁶ ₆ ⁷ ₇ ⁸ ₈ ⁹ ₉ ¹⁰ ₁₀ ¹¹ ₁₁ ¹² ₁₂ ¹³ ₁₃ ¹⁴ ₁₄ ¹⁵ ₁₅ ¹⁶ ₆₁₂ ⁶¹³ ₆₁₃ ⁶¹⁴ ₆₁₄ ⁶¹⁵ ₆₁₅ ⁶¹⁶ ₆₁₆ ⁶¹⁷ ₆₁₇ ⁶¹⁸ ₆₁₈ ⁶¹⁹ ₆₁₉ ⁶²⁰ ₆₂₀ ⁶²¹ ₆₂₁ ⁶²² ₆₂₂ ⁶²³ ₆₂₃ ⁶²⁴ ₆₂₄ ⁶²⁵ ₆₂₅ ⁶²⁶ ₆₂₆ ⁶²⁷ ₆₂₇ ⁶²⁸ ₆₂₈ ⁶²⁹ ₆₂₉ ⁶³⁰ ₆₃₀ ⁶³¹ ₆₃₁ ⁶³² ₆₃₂ ⁶³³ ₆₃₃ ⁶³⁴ ₆₃₄ ⁶³⁵ ₆₃₅ ⁶³⁶ ₆₃₆ ⁶³⁷ ₆₃₇ ⁶³⁸ ₆₃₈ ⁶³⁹ ₆₃₉ ⁶⁴⁰ ₆₄₀ ⁶⁴¹ ₆₄₁ ⁶⁴² ₆₄₂ ⁶⁴³ ₆₄₃ ⁶⁴⁴ ₆₄₄ ⁶⁴⁵ ₆₄₅ ⁶⁴⁶ ₆₄₆ ⁶⁴⁷ ₆₄₇ ⁶⁴⁸ ₆₄₈ ⁶⁴⁹ ₆₄₉ ⁶⁵⁰ ₆₅₀ ⁶⁵¹ ₆₅₁ ⁶⁵² ₆₅₂ ⁶⁵³ ₆₅₃ ⁶⁵⁴ ₆₅₄ ⁶⁵⁵ ₆₅₅ ⁶⁵⁶ ₆₅₆ ⁶⁵⁷ ₆₅₇ ⁶⁵⁸ ₆₅₈ ⁶⁵⁹ ₆₅₉ ⁶⁶⁰ ₆₆₀ ⁶⁶¹ ₆₆₁ ⁶⁶² ₆₆₂ ⁶⁶³ ₆₆₃ ⁶⁶⁴ ₆₆₄ ⁶⁶⁵ ₆₆₅ ⁶⁶⁶ ₆₆₆ ⁶⁶⁷ ₆₆₇ ⁶⁶⁸ ₆₆₈ ⁶⁶⁹ ₆₆₉ ⁶⁷⁰ ₆₇₀ ⁶⁷¹ ₆₇₁ ⁶⁷² ₆₇₂ ⁶⁷³ ₆₇₃ ⁶⁷⁴ ₆₇₄ ⁶⁷⁵ ₆₇₅ ⁶⁷⁶ ₆₇₆ ⁶⁷⁷ ₆₇₇ ⁶⁷⁸ ₆₇₈ ⁶⁷⁹ ₆₇₉ ⁶⁸⁰ ₆₈₀ ⁶⁸¹ ₆₈₁ ⁶⁸² ₆₈₂ ⁶⁸³ ₆₈₃ ⁶⁸⁴ ₆₈₄ ⁶⁸⁵ ₆₈₅ ⁶⁸⁶ ₆₈₆ ⁶⁸⁷ ₆₈₇ ⁶⁸⁸ ₆₈₈ ⁶⁸⁹ ₆₈₉ ⁶⁹

In operation, each wing portion 34, or more specifically the friction means 52 thereon, is caused to engage the inboard friction means or surface 50 on the associated column by the action of the related shoe 62 which is urged upwardly against surface or wedge means 56 on the associated wing portion 34, the shoe sliding on its surface 60 toward the related outboard column surface or friction means 66 for engagement therewith. The spring 72, which is compressed between the shoe and the casting, or part of the side frame structure 76, supports the shoe and thus in turn supports the bolster and is further compressible on downward movement of the bolster whereby greater friction is developed. The spring 72 is compressed directly between the seat 76 and the shoe, thus eliminating complicated assemblies such as nuts and bolts which are expensive and known to become loose in service.

It will be realized that in service the pocket 41 in each extension serves to collect dirt, as hereinbefore stated, which would otherwise sift from the top of the extension between the wedge surfaces on the shoe and the extension or between the engaging surfaces on the shoe and the column or between the extension and column surfaces, and cause malfunctioning of the friction means or

4

abrade these surfaces and thus shorten the life of the arrangement.

To disassemble the arrangement described, the bolster is elevated to the top of the bolster opening 8, thereby relieving the pressure on the truck springs 20 and the shoe-actuating springs 72. These springs are removed, whereupon the friction shoes drop to the bottom of the respective columns and are removed through the bolster opening. The spring plate and spring seat castings are then removed. The bolster is then lowered into the widened portion 106 of the bolster opening and removed in usual manner. It will be noted that the vertical extent of the wing portions 34 is less than the distance between the lower edges of the associated portions of the inboard and outboard column walls and the adjacent secondary truss web 84. To assemble the truck the procedure is reversed.

A modification of the invention is illustrated in Figures 5 and 6 wherein parts corresponding to those in Figures 1 to 4 are identified by corresponding numerals. In the instant modification the invention is shown as applied to a car truck of a type wherein the top chord 16 of the side frame is provided with integral inboard and outboard flanges 200 and 202. The inboard wall 44 is considerably shorter than that shown in the preferred embodiment in order to accommodate insertion and removal of the bolster through the lower portion of the bolster opening 8 above the inboard flange 200. The shoe-actuating spring 72 in this modification seats at its lower end as at 204 against the top chord 16 of the tension member 2 of the side frame and is positioned on said chord 16 by means of an integral upstanding boss 208 formed on said top chord.

208 formed on said top chord. In operation, the surface 60 of the friction shoe 62 is caused to slide as at 58 against the surface 56 on the associated bolster wing portion 34 by the reaction of spring 72 and to engage the outboard surface 66 on the associated column, whereupon the wing portion 34 is urged against the inboard surface 50 on the associated column. 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540

Another modification of the invention is illustrated in Figures 7 to 9 wherein parts corresponding to those in Figures 1 to 6 are identified by corresponding numerals. In the present embodiment vertical movement of the bolster is controlled by substantially constant friction. The bolster 24, as in the previous embodiments, comprises a laterally extending wing portion 300 at each side thereof projecting into the adjacent side frame channel 42 between the spaced inboard and outboard friction surfaces 50 and 66. The wing portion 300 comprises a substantially vertical wall or web 302 on its inboard side, the web 302 extending transversely of the bolster and merging at one of its lateral edges with the adjacent side wall 30 of the bolster. The wing portion 300 also comprises a pair of ledges 304 and 306 spaced laterally of the bolster and at their lower ends merging with the inner side of the wall 302 of the wing portion intermediate the top and bottom edges thereof. The ledge 304 which is adjacent the bolster is connected at one of its lateral edges to the adjacent side wall of the bolster, and the connection between the ledge 306, which is remote from the bolster and the vertical wall 302 of the wing portion, is reinforced by a transverse vertical interconnecting end wall 307.

83 connecting end wall 307. The ledges 304 and 306 together with web 302 and wall 30 of the bolster and wall 307 form pockets 309 and 311, as clearly seen in Figure 9, these pockets being open to the top of the associated bolster extension 300 and being adapted to collect dirt which might otherwise 85 become lodged between the various surfaces on the ledges

and the shoe and the column as hereinafter described. The pockets 309 and 311 are open to the space therebetween whereby the dirt may sift into the space and fall clear of the surface.

The spaced ledges 304 and 306 provide convex coplanar diagonal wedge surfaces 308 and 310 sloping upwardly toward the related outboard friction surface 66 of the associated column 6.

A friction shoe 312 is housed within the column, said shoe being of skeletal construction somewhat cup-shaped in form and comprising a substantially horizontal spring seat wall 314 at its upper end, a substantially vertical friction wall 316 engaging surface 66 on the associated column, a rear wall 322, and side ledges 324 and 326, said ledges 324 and 326 being connected to the front and rear walls 316 and 322 and presenting on their upper edges convex coplanar, diagonal wedge surfaces sloping upwardly toward the related column surface 66 and engaging surfaces 308 and 310 on ledges 304 and 306, respectively, of the associated bolster wing portion. The shoe is actuated by a spring 328 housed therewithin and extending between the wedge surfaces on the shoe and against the bottom of the spring seat wall 314 of the shoe and at its lower end reacting as at 330 against a substantially horizontal shelf or web 332 disposed below the shoe and extending laterally of wall 302 of the wing portion and integral with the lower edge thereof. The spring 328 which is under compression slides the shoe on its ledges 324 and 326 against the bolster wing ledges 304 and 306 along surfaces 308 and 310 thereon and urges the shoe in an outboard direction with respect to the frame to engage the front wall 316 of the shoe with the related column surface 66. The bolster wing portion is simultaneously urged in a direction inboardly with respect to the frame whereby the friction plate 334, which is secured to the external side of the wall 302 as by welding at 336, is caused to engage the related inboard column surface 50.

To disassemble this truck, the bolster 24 is elevated to the upper end of the bolster opening, the bolster-supporting springs 20 are removed, and the bolster is then lowered to the bottom of the bolster opening. It will be noted that the inboard column wall 44 is terminated far enough above the inboard flange 200 of the side frame in order to accommodate the passage of the related bolster wing portion into and out of the bolster opening, as will be readily understood by those skilled in the art.

In assembling the truck arrangement shown in Figures 7 to 9, the spring 328 is inserted into the shoe and then seated on the web 332 of the associated bolster wing portion, and then the shoe is urged inwardly into said wing portion and held therein by means of any suitable fixture or jig (not shown). The bolster with the shoes in the respective wing portions is then inserted through the inboard side of the frame and elevated within the bolster opening, whereupon the fixtures holding the shoes are removed. The bolster is elevated to the upper end of the bolster opening and the truck springs are inserted into the bolster opening. Thereafter the truck bolster is lowered onto the springs.

It will be understood that in all of the embodiments described, the shoe-actuating spring reacts directly between the shoe and one of the truck members; that the trucks are simple to assemble and disassemble; that the cooperation between the shoes, the bolster wings, and the columns snub various movements of the bolster on the truck springs and relative to the side frame; that the friction means maintain the bolster and the side frame in squared relationship; and that the engagement between the bolster wings and the shoes is along curved surfaces which accommodate angling of the bolster without disengaging the shoes from the columns. It will also be observed that the wing portions of the bolster are of skeletal, light construction in accordance with good foundry practice and that the various webs forming the wing portions are arranged to provide dirt-collecting pockets in the top sides of the wing portions.

It will further be noted that in all embodiments longitudinal vertical angling of the bolster is effectively controlled. As shown in the drawings, each shoe and associated wing normally engage each other at points located between the top and bottom of the wing. The wing and the shoe, however, also engage the column above and below these points. The bolster, on angling, rocks

on its wings against the shoes, whereupon the wings fulcrum against the column above or below their points of engagement with the respective shoes and constantly shift the points of engagement further away from the point of fulcrum, thereby constantly increasing the leverage on the respective shoes and moving the shoes downwardly against the compression of the shoe actuating springs and the friction resistance developed between the shoes and the columns.

It will be understood that the bolster wings in the various embodiments may be arranged to engage the outboard column surfaces and provided with wedge faces facing the inboard column surfaces, and that the shoes may be wedged between the wedge faces and the inboard surfaces.

I claim:

1. In a truck, a side frame member comprising spaced columns and an intervening bolster opening, each of said columns having inboard and outboard walls, a bolster member within said opening with lateral portions between the walls of respective columns, spring means supporting the bolster member from the side frame, a friction shoe within each column having an area of engagement with the related outboard wall and in wedge engagement with the adjacent bolster portion and urging the portion into an area of engagement with the inboard wall of the associated column, and a spring reacting directly against each shoe and one of said members, each shoe and the related bolster portion engaging each other along convex surfaces thereon sloping upwardly longitudinally of the bolster toward the outboard side of said frame and accommodating longitudinal vertical angling of the bolster without disengaging the shoes from the respective outboard column walls, each bolster portion extending above and below its normal area of engagement with the associated shoe and on longitudinal vertical angling of the bolster fulcruming against the associated inboard column wall above or below its normal area of engagement with the associated shoe and shifting its area of engagement with the point of fulcrum to obtain maximum leverage against the associated shoe.

2. In a railway bolster, a box-section member including spaced interconnected top and bottom and side webs, outwardly projecting wings on opposite sides of said member, each wing comprising a substantially vertical web on its inboard side extending transversely of the bolster and connected at its inner edge with the adjacent bolster side web, a pair of spaced ledges at the outboard side of said wing connected at their lower ends to the outboard side of said vertical web intermediate the top and bottom margins thereof and presenting downwardly facing substantially coplanar wedge faces sloping upwardly toward the adjacent end of said bolster, one of said ledges being connected to the adjacent bolster side web, a substantially vertical wall connected to the other of said ledges and said vertical web at the edges thereof remote from said bolster, a shelf spaced below said ledges and connected to said vertical web, and a friction plate carried by said vertical web.

3. In a railway car truck, a side frame comprising tension and compression members and an upright column therebetween, presenting opposed inboard and outboard friction surfaces, said surfaces extending longitudinally of the frame, a bolster having an end portion spring-supported from the tension member and having a wing extending from the end portion between said surfaces and directly engaging one thereof, a shoe beneath said surfaces and wedged between the wing and the other of said surfaces, and spring means engaging the shoe and tension member and arranged to actuate said shoe to the wedged position thereof, the area of engagement of said wing with said one surface extending from the top to the bottom of said end portion and the area of engagement between the shoe and the wing being located intermediate the top and bottom of said end portion, said shoe and wing having rolling contact with each other, whereby when said bolster angles longitudinally downwardly toward the shoe, the wing is caused to roll up on the shoe to effect maximum actuation of the shoe against the compression of the spring means and thereby provide a maximum resistance to said angling, and when said bolster angles upwardly away from the shoe, the wing is caused to roll off the shoe to decrease the lev-

erage thereagainst, thereby decreasing actuation of the shoe to a minimum.

4. A truck according to claim 1, wherein the spring associated with each shoe reacts directly against the related shoe and bolster member.

5. A truck according to claim 1, wherein the spring associated with each shoe reacts directly against the related shoe and side frame member.

6. A truck according to claim 1, wherein the area of engagement between each shoe and the related outboard wall extends above the area of engagement between the associated bolster portion and inboard wall.

7. A truck according to claim 1, wherein the area of engagement between each bolster portion and inboard wall extends below the area of engagement between the related shoe and outboard wall.

8. A truck according to claim 1, wherein the area of engagement between each shoe and outboard wall is hori-

zontally aligned with the area of engagement between the related bolster portion and inboard wall.
